UNITED STATES PATENT OFFICE.

THOMAS H. NEWTON AND SAMUEL POLINSKY, OF NEW YORK, N. Y., ASSIGNEES TO
DEFIANCE BUTTON MACHINE COMPANY, OF NEW YORK, N. Y., A CORPORATION OF
NEW YORK.

TUFTING BUTTON.

Application filed July 30, 1926. Serial No. 125,887.

Our invention is a tufting button for mattresses, and for upholstery generally, whereby provision is made for the secure attachment of a button to a loop of a tufting 5 thread.

The object in view is to attach a button with facility to a thread loop and to retain such button in effective engagement with said loop, said attaching and retaining 10 means being unitary with the button.

The invention consists of a button the back member of which is provided with a tongue of novel formation operable by snapping the tongue into engagement with the 15 loop of a tufting thread, said tongue being characterized by the provision of members extending sidewise from the respective edges of the tongue and spaced relatively thereto in order to leave openings for receiving the 20 two strands of the looped thread.

Other functions and advantages of the invention will appear from the following description taken in connection with the drawings, wherein—

25 Figure 1 is a perspective view of a mattress with our button applied to the thread loops thereof.

Figures 2 and 3 are views in vertical section illustrating a part of the mattress with 30 our button attached to the thread loop.

Figure 4 is an under plan view of the button illustrating the function of the tongue back.

Figure 5 is an edge view of the button 35 back showing the tongue.

Figure 6 is an enlarged sectional view of the button back and the engagement of the thread loop with the tongue, the section being taken on the line 6—6 of Figure 5.

40 In a practical form, our invention is embodied in a button comprising a plurality of metal "moulds" or shells, with or without a fabric covering for the front mould or shell. As shown, the button comprises a front shell or mould A, a back shell or mould B, and an encasing member, such as a fabric C for the front shell, the several parts being assembled and united for the marginal edges of the two shells to be interlocked with each 45 other and to confine and grip the edge part of the fabric.

The back member B has a tongue D of novel formation, said tongue being struck up from the metal comprising the member and affording means whereby the button as 50

an entirety may be snapped into engagement with facility on a thread loop of the mattress or other upholstered article.

According to our invention, the tongue D is provided with wings E extending sidewise 60 from the respective edges of said tongue and at the free end thereof. The tongue is usually inclined at an angle to the plane of the shell B, so that the tongue and the wings thereof are in offstanding relation to the 65 plane of the button back, thus providing for the entry of the thread loop into the space between the button back and the tongue. The wings E extend backwardly from the end of the tongue and they are spaced relatively to the side edges of said tongue, thus resulting in the formation of notches or openings, e, which are bounded partly by the edges of the wings E, and partly by the edges of the inclined tongue D. 75

The tongue and the lateral wings thereof present an arcuate edge f the length of which is equal to the combined width of the tongue and the distance of the wings from the axial line of said tongue, said extended 80 arcuate edge f constituting a prolonged edge beneath which the thread loop passes, and said edge functioning as a guide for the entry of the thread loop, whereby the button is attachable with facility to the thread loop. 85

The tongue and the wings thereof are stamped or struck up from the metal composing the shell or button back B, and in such stamping operation the metal is cut or slitted along defined lines to result in the 90 tongue and the lateral wings, and in addition thereto, the metal is so slitted or cut as to result in the formation of lips g, g, the latter being due to the notches or spaces e, e, at the respective sides of the tongue D and in rear 95 of the wings E. These lips g, g, are opposite to the notches e, e, and they are desirably deflected at an angle to the inner face of the shell or mould B. By the formation of the lips opposite to the notches e, e, and the inclination of such lips in an opposite direction to the inclination of the tongue D, there is ample space for the reception of the strands of the looped thread, thus contributing to the facility of the attachment of the button 100 to the looped thread. 105

It may be desirable to provide a seat on the tongue for the engagement of the thread loop, and we make such provision by bending or deflecting the tongue D intermediate 110

the wings E and the line at which the tongue joins with the metal of the shell B, said bending of the tongue producing a curved part h functioning as a seat for the reception of the thread loop.

As illustrative of the mode of using the button, we have shown it in connection with a thread loop I of a mattress, or other upholstered article, J in Figures 1, 2 and 3 of the drawings. As there shown, the loop i of a thread is exposed on the top or face of the mattress, and with said loop i engages the tongue D and wings E of the button. To so engage the button, the arcuate edge f is inserted between the loop i of the thread and the mattress, and pressure is applied edgewise to the button, as a result of which the tongue D slips into the loop and the thread enters the notches e, e, in opposite sides of the tongue D. The wings E, E, and the respective edges of the tongue are in contact with the strands of the thread loop, and the lips g coact to a certain extent with the tongue and with the wings, and in a manner to retain the button in the required engagement with the thread. The button is thus attached with facility to the thread loop, and the peculiar formation of the tongue and of the wings act to retain the button in the required secure engagement with the thread loop, all of such attaching and retaining means being unitary with the button. The tongue, the wings, and the lips are formed as parts of the shell B within the marginal edges thereof, thus producing in a simple economical structure a self-attaching element which is of such relation to the shell B that the latter may be united as usual with the shell A and the fabric cover C.

Having thus fully described the invention, what we claim as new and desire to secure by Letters Patent is:

1. In tufting button, a tongue provided with wings extending sidewise from the tongue and forming therewith a plurality of thread-loop receiving notches.
2. A tufting button provided on the back thereof with an integral tongue inclined to the plane of said back, and a plurality of wings extending from the side edges of the tongue and forming therewith a plurality of notches at the respective sides of the tongue.
3. A tufting button provided on the back thereof with an integral tongue in offstanding relation to the back, and a plurality of wings extending from the respective side edges of the tongue, the free end of the tongue and the wings being of arcuate formation.
4. In a tufting button, a back shell or mould provided with a tongue and with a plurality of wings extending from the tongue and spaced relatively to the side edges thereof to produce a plurality of notches, said tongue and the wings being struck up from the metal of the back shell or mould.
5. In a tufting button, a back shell or mould provided with a struck up tongue and with a plurality of wings integral with the tongue and spaced relatively to the side edges thereof to produce a plurality of notches, and lips integral with the back shell or mould and positioned opposite to the notches.

In testimony whereof we have hereto signed our names this 22 day of July, 1926.

THOMAS H. NEWTON.
SAMUEL POLINSKY.
